DESIGN FOR A RETURN POST CARD BLOTTER

Samuel J. Bienstock, New York, N. Y.

Application July 10, 1936, Serial No. 63,764

Term of patent 14 years

To all whom it may concern:

Be it known that I, Samuel J. Bienstock, a citizen of the United States and residing at New York city, in the county of Bronx and State of New York, have invented a new, original, and ornamental Design for a Return Post Card Blotter, of which the following is a specification, reference being had to the accompanying drawing, forming part thereof, and in which

The figure is a perspective view of a return post card blotter showing my design.

The design on the blotter calls attention to the return post card inserted in the slotted construction.

I claim:

The ornamental design for a return post card blotter substantially as shown and described.

SAMUEL J. BIENSTOCK.
